UNITED STATES PATENT OFFICE.

WILSON D. ANDERSON, OF BREMERTON, WASHINGTON.

VENDING DEVICE.

Application filed April 25, 1921. Serial No. 464,092.

To all whom it may concern:

Be it known that I, WILSON D. ANDERSON, a citizen of the United States, residing at Bremerton, in the county of Kitsap and 5 State of Washington, have invented certain new and useful Improvements in Vending Devices; and I do hereby declare the following to be a full, clear, and exact description of the invention, such as will enable others 10 skilled in the art to which it appertains to make and use the same.

The object of the invention is to provide a simple and attractive vending device whereby a legitimate stimulation of trade may be 15 afforded by offering for sale objects having a commercial value corresponding with the amount charged or demanded of a purchaser for the privilege of making a selection with the possibility of winning a premium determinable by designating characters which are normally concealed and which may be individually exposed by the selection and removal from the apparatus of the article purchased; and with this object in view the invention consists in a construction and combination of parts of which a preferred embodiment is shown in the drawing, wherein:

Figure 1 is a view of an apparatus embodying the invention, certain of the vendible objects being omitted to expose the designating characters by which they are normally concealed from the purchaser.

Figures 2 and 3 are detail views showing minor modifications of the same construction.

The apparatus consists essentially of a base 10, which may be of any suitable material such as wood, card-board, paper-board or the like having seats or bases arranged in 40 intersecting longitudinal and transverse columns or in any preferred relation with the objects of adding to the attractiveness of the device, such bases or seats being distinguishably designated as by means of numerals as shown.

To the surface of the base within these spaces or upon said seats and in concealing relation with the designating characters thereon are adhesively but detachably secured the vendible articles such as collar buttons 11, or the equivalent thereof, for which a legitimate charge of five cents or ten cents or more may be made, it being the purpose to use regularly recognized commercial objects as the means by which the designating characters of the seats are normally concealed and a selection of which, all being of substantially the same construction and form, must be made by the purchaser in order to obtain the advantage of 60 a premium offered for the exposure of a lucky number or designating character in accordance with the legend appearing on the board or represented suitably in connection therewith by the vendor.

A purchase having been made it is the privilege of the purchaser to make a selection of the articles offered for sale and displayed on the base or board, and the detachment of the selected article serves to expose 70 the designating character, which, if that of the premium, entitles the purchaser to the latter.

In the construction illustrated in Figure 1, the designating characters are applied directly to the surface of the base or board, the base of the collar button being adhesively secured to said surface, while in Figure 2 the surface of the base bearing the designating characters is covered by a supplemental 80 semi-transparent sheet 12 to which the vendible objects are adhesively secured, a dotted tearing line 13 being arranged around the base of said objects so that a portion of the covering sheet is designed to be removed 85 with the object when the latter is detached. In the construction illustrated in Figure 3 the designating character is inscribed upon a separate folded strip or blank 15 confined by and concealed under the base of the 90 vendible object.

Having thus described the invention, what I claim is:

1. A vending device consisting of a base, means on said base to determine the winner 95 of a contest, vendible articles exposed to the view of and for sale to and removal by entrants in such contest, and means removably securing said articles on the base in concealing relation to said means.

2. A vending device consisting of a base, means on said base to determine the winner of a contest, vendible articles exposed to the view of and for sale to and removal by entrance in such contest, covering sheets for 105 said means, one sheet being associated with and secured to the base and to each article whereby upon removal of an article the attached sheet will be torn.

3. A vending device consisting of a base, 110 means on said base to determine the winner of a contest, vendible articles exposed to the view of and for sale to and removal by entrance in such contest, covering sheets of semi-transparent material exposed over said one sheet being associated with and secured by adhesive to said article and by adhesive to the base whereby upon removing an article the attached sheet will be torn.

In testimony whereof I affix my signature in presence of two witnesses.
